UNITED STATES PATENT OFFICE

96,402

DESIGN FOR AN INVENTORY CALCULATING MACHINE

William E. Mackelfresh, Jr., Chicago, Ill., as-
signor to The Robert Britigan Corporation,
Chicago, Ill., a corporation of Illinois

Application March 28, 1935, Serial No. 56,100

Term of patent 14 years

To all whom it may concern:

Be it known that I, William E. Mackelfresh, Jr., a citizen of the United States of America, residing at 720 North Michigan Avenue, Chicago, Illinois, have invented a new, original, and ornamental Design for an Inventory Calculating Machine, of which the following is a specification, reference being had to the accompanying drawing, forming a part thereof.

Fig. 1 is a top plan view, Fig. 2 is an end elevation, Fig. 3 is a front elevation and Fig. 4 is a perspective view of my inventory calculating machine.

I claim:

The ornamental design for an inventory calculating machine substantially as shown.

WILLIAM E. MACKELFRESH, JR.
